UNITED STATES PATENT OFFICE

ERICH MÜLLER, OF SPANDAU, NEAR BERLIN, GERMANY

PIPE STOPPING APPARATUS

Application filed May 29, 1930, Serial No. 457,467, and in Germany November 1, 1928.

The present invention relates to an apparatus for filling tobacco pipes in which levers and feed screws are used for filling the pipe. Till now, other appliances of this kind have failed, because, on account of the unsuitable arrangement of their levers and spirals, preventing filling the pipes as firmly as absolutely necessary, they were unable to work properly.

According to the present invention, these drawbacks are entirely done away with in a simple manner by the arrangement, inside the tobacco reservoir, of a cylindrically wound feed screw into which, along its whole length, tobacco is fed by means of a spring-pressed partition-plate arranged laterally and serving as a tobacco press. By turning a handle provided outside the tobacco reservoir and standing in connection with the said spiral feed screw, the latter is rotated. This feed screw having a roughened surface, catches the tobacco and draws it into its cavity. From there, when the spiral feed screw turns, the tobacco is pressed towards the opening in the reservoir to which adjoins the opening of the pipe-bowl. Thus the tobacco is forced firmly into pipe as required by smokers.

The accompanying drawings show, as an example, one form in which the apparatus can be carried out, i. e. Fig. 1 is a plan of the pipe filling apparatus, Fig. 2 shows the apparatus seen from above, Fig. 3 is the partition plate for conducting the tobacco within the reservoir, and Fig. 4 is the same plate seen from above.

The tobacco reservoir 1 is provided with a lid 10, 10' consisting of two parts. Part 10' is firmly attached, while part 10 of the lid is loosely joined to the firm part 10' by means of a hinge 12.

Inside the reservoir 1 the feed screw 2 is arranged carried by a tube 3 and, below, supported in a guide-box 17. A stop-ring 4 fixed at the tobacco reservoir 1 prevents the feed screw member with tube 3 from moving up and down. At its upper end tube 3 is provided with a suitable handle by means of which it can be turned with the feed screw member. The handle consists of two parts 5 and 7 connected with each other by a hinge

6, so that it can be folded up. Part 7 carries a pin 8 over which a tube 9 is slid serving as handle. When folding the handle, handle 9 engages into the cavity of tube 3.

In reservoir 1 a spring pressed partition plate 16 is arranged provided with spring bearing boxes 13 into which springs 15 engage resting on spring supports 14 and constantly tending to press plate 16 inwards. This arrangement forms a tobacco press for the purpose of pressing the tobacco towards the whole length of the feed screw member 2. If, after opening the lid 10, tobacco is filled into the reservoir 1, the plate is pressed back against the pressure of springs 15, so that the chambers α and α' can be filled up with tobacco.

The end 18 of the guide-box 17 projecting downwards, is suitably provided with a screw-thread in order to screw itself into the pipe-bowl, the cone-shaped end adapting itself to different openings of the pipe-bowls.

The manipulation of the new pipe filling apparatus is as follows:

When reservoir 1 is filled with tobacco and the projecting end 18 of box 17 is placed on the pipe-bowl, handle 9 is turned to the right, in consequence of which the member 2, which is somewhat roughened on its surface, grips into the tobacco and draws it into the cavity of the spiral member, whereupon the latter presses the tobacco firmly into the pipe-bowl. Plate 16 always keeps on pressing the tobacco, so that the member 2 can always grip tobacco along its whole length. When the pipe-bowl is filled up with tobacco, handle 9 is turned to the left. Thereby the tobacco is pressed back again so that nothing of it can fall out at the pipe-opening, and the lower opening is closed by a lid.

Claims:

1. A device of the class described comprising a container, a cylindrically wound feed screw in the container, the sides thereof being parallel to the longitudinal axis thereof, a spring-pressed plate in the container for forcing tobacco around the feed screw, said plate having its face disposed parallel with respect to the longitudinal axis of the feed screw.

2. A device as claimed in claim 1, wherein the outer faces of the spirals forming the feed screw are roughened.

3. A device of the class described comprising a container, a tube extending into the container, a cylindrically wound feed screw having its upper end connected with the tube, a guide box fixed to the bottom of the container and in which the lower end of the feed screw engages, a plate movable transversely within the container, springs in the container for forcing the plate toward the feed screw, said plate being disposed in parallel relation with respect to the longitudinal axis of the tube and feed screw.

In testimony whereof I have signed my name to this specification.

ERICH MÜLLER.
